(57) **CLAIM**

We claim the ornamental design for a litter scoop, as shown and described.

DESCRIPTION

FIG. 1 is a top perspective view of a litter scoop showing our new design;

FIG. 2 is a bottom perspective view thereof;

FIG. 3 is a right side elevation view thereof; and,

FIG. 4 is a cross-sectional view thereof taken on line 4—4 of FIG. 1.

1 Claim, 2 Drawing Sheets

FIG. 1

FIG. 2
